UNITED STATES PATENT OFFICE

LEWIS F. ALTFATHER, OF BERLIN, PENNSYLVANIA, ASSIGNOR OF ONE-THIRD TO JOHN CALVIN ALTFATHER AND ONE-THIRD TO RALPH MAC TAYLOR, BOTH OF BERLIN, PENNSYLVANIA

POTATO CUTTER

Application filed June 10, 1930. Serial No. 460,206.

This present invention relates to a potato cutter and has for its prime object to provide a machine of this nature which may be power driven in order to obtain speed in the cutting of spud potatoes and the like.

Another very important object of the invention resides in the provision of a machine of this nature having a plurality of cutting frames mounted in a rotary table in combination with a follower block for forcing potatoes through the frames, and means for simultaneously operating the follower block and rotating the table in proper coordination so that the block will force a potato through a cutting frame as it arrives thereunder.

A still further very important object of the invention resides in the provision of a potato cutting machine of this nature which is exceedingly simple in its construction, inexpensive to manufacture, strong and durable, compact and convenient in its arrangement of parts, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a machine embodying the features of my invention,

Figure 2 is a vertical longitudinal section therethrough,

Figure 3 is a plan view of one of the cutting frames with the knives therein,

Figure 4 is a transverse section thereof taken substantially on the line 4—4 of Figure 3,

Figure 5 is an end elevation of the machine,

Figure 6 is a perspective view of the connecting rod,

Figure 7 is a perspective view of the crank shaft,

Figure 8 is a perspective view of the bell crank lever,

Figure 9 is a perspective view of one of the longitudinal knives,

Figure 10 is a fragmentary side elevation of the machine,

Figure 11 is a perspective view of the follower blocks,

Figure 12 is another perspective view 55 thereof showing the arms attached thereto,

Figure 13 is a top plan view of the machine showing the table removed,

Figure 14 is a perspective view of one of the cross knives, 60

Figure 15 is a perspective view of the elongated catch,

Figure 16 is a bottom plan view of the turn table showing a portion of the bottom plate broken away, 65

Figure 17 is a fragmentary vertical transverse section taken substantially on the line 17—17 of Figure 10,

Figure 18 is a fragmentary vertical transverse section taken substantially on the line 70 18—18 of Figure 10, and

Figure 19 is a detail sectional view through the table.

Referring to the drawing in detail, it will be seen that the numeral 5 denotes an elongated table mounted on suitable supporting legs 6 and having one end 5' in the form of 75 a seat. A cylinder 7 rises from the platform 5 to receive in its upper end a ring 8 on the center of a table T. This table T comprises 80 spaced block segments 9 about a center square block 10 and sheet metal plates 11 are disposed on the bottoms and tops of the blocks and a peripheral ring 12 is disposed about the outer edges of the block. The spaces between the blocks are denoted by numerals 14 and in these spaces are anchored rectangular cutting frames 15 having a plurality of parallel spaced cross knives 16 and a longitudinal 85 knife 17 in each frame. The longitudinal knife has slots 18 rising from the bottom edge thereof to receive the central portions of the transverse knives which have V-shaped notches 19 in their central portions merging into slots 20. On the ends of the longitudinal knife 17 there are ears 21 which are secured to the ends of the frame and the ends of the transverse knives 16 have their corners formed with notches 22 to rest on the sides 90 of the frame.

Figure 23 is a detail view of the longitudinal knife 17 showing the ears 21 and the notches 22, 95

Figure 24 is a detail view of the transverse knife 16 showing the notches 19 and the slots 20, 100

Figure 25 is a detail view of the connecting rod 26 showing the bearing 27 and the bearing 28, 105

Figure 26 is a detail view of the crank shaft 29 showing the bearing 30 and the bearing 31, 110

Figure 27 is a detail view of the bell crank lever 32 showing the bearing 33 and the bearing 34, 115

Figure 28 is a detail view of the longitudinal knife 17 showing the ears 21 and the notches 22, 120

Figure 29 is a detail view of the transverse knife 16 showing the notches 19 and the slots 20, 125

Figure 30 is a detail view of the connecting rod 26 showing the bearing 27 and the bearing 28, 130

Figure 31 is a detail view of the crank shaft 29 showing the bearing 30 and the bearing 31, 135

A bolt 24 extends through an opening in the lower plate 11 and through the platform 5 to hold the table against displacement but permitting it to rotate on the cylinder 7. Rests 25 and 26 rise from the platform 5 under the table T adjacent its periphery. A dog 27 is pivotally mounted as at 28 to engage with recesses 29 in the bottom of the table for holding it in stationary position as will be more clearly explained hereinafter. A spring 30 holds the pawl in engaging position.

The numeral 31 denotes a follower block having slots 32 in the bottom face thereof to accommodate the knives 16 and 17. Arms 33 are fixed to the sides of the block and are rockably mounted on a rod 34 in a U-shaped support 35 rising from the platform 5. A rod 36 is disposed between intermediate portions of the arms 33. A connecting rod 37 has an arcuate end 38, the terminal of which is rockably engaged with the rod 26. A crank shaft 39 is journaled in bearings 40 on the platform 5 across an opening 41 and has an intermediately disposed crank portion 42 with which the lower end of the connecting rod 37 is engaged.

On one end of the crank shaft 39 is a crank arm 43 with which is pivotally engaged as at 44 an L-shaped catch 45, the terminal of the longer arm of which has a catch head 46 for engaging the recesses 29. A bell crank lever 47 is pivotally mounted as at 48 in the rest 26 and a spring 49 is engaged with the lower end of this bell crank to hold the upper end which has an offset extension 50 in engagement with the catch 45 to hold it in engaging position. A guide is provided for the catch 45 as is particularly well illustrated in Figure 17 and comprises an inner member 50 rising from the platform and braced as at 51 and an outer member 52 which is hingedly mounted as at 53 with the base portion 54 of the member 50 and is urged toward the member 50 by means of a bolt 55 having a spring 56 associated therewith.

A platform 60 is hingedly mounted as at 61 on one of the end supporting legs and is adjustably mounted in desired position by means of a rod 62 by means of adjusting nut 63. This rod 62 is engaged with the adjacent end of the platform 5. A motor 64 is mounted on the platform 60 and has a pulley 65 on the armature shaft thereof. A pulley 66 is on the crank shaft 39 and an endless belt or the like 67 is trained over these pulleys 65 and 66. Obviously by adjusting the platform 60 the desired tension may be obtained on this belt 67.

When the motor 64 is in operation and the operator is sitting on the seat portion 5' of the platform 5, it will be seen that an intermittent rotary motion is imparted to the table and when the table momentarily stops then the follower block is swung downward-

ly to force the potatoes through the knives of the frame thereunder. The operator, of course, places the potatoes on the frames as they come to rest in front of him and so places the potatoes on the knives of the frame depending upon the number of pieces he desires to cut the potato into as will be quite apparent. It will be noted that when the crank arm 43 is actuating the catch 45 to the left, referring particularly to Figure 10, said catch engages the dog to release it from its recess and this dog will be released in time to engage the next oncoming recess because at this time the crank arm will be swinging in the lower arc of its movement.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination, a table, means for rotatably mounting the table, a plurality of cutting frames in the table, a follower block for forcing a potato through the frames, arms on the block, means for swingably mounting the arms, means for oscillating the arms to swing the block into engagement with one of the frames which is disposed thereunder, means for imparting intermittent rotary motion to the frame, said last mentioned means comprising a shaft having a crank arm thereon, a catch pivotally engaged with the crank arm and having a catch head engageable with recesses in the bottom of the table, means for holding the catch into engagement with the table, said last mentioned means comprising a crank shaft having a spring engaged therewith to urge one end of the crank shaft in engagement with the catch to hold it in engagement with the table.

2. In combination, a table, means for rotatably mounting the table, a plurality of cutting frames in the table, a follower block for forcing a potato through the frames, arms on the block, means for swingably mounting the arms, means for oscillating the arms to swing the block into engagement with one of the frames which is disposed thereunder, means for imparting intermittent rotary motion to the frame, said last mentioned means

comprising a shaft having a crank arm thereon, a catch pivotally engaged with the crank arm and having a catch head engageable with recesses in the bottom of the table,
5 means for holding the catch into engagement with the table, said last mentioned means comprising a crank shaft having a spring engaged therewith to urge one end of the crank shaft in engagement with the catch to
10 hold it in engagement with the table, a stop pawl engageable with the recesses, spring means normally holding the pawl in engagement with the recesses, said pawl being in the path of movement of the catch
15 so as to be released when the catch is in engagement with a recess and is in the act of rotating the table.

3. In combination, a table, means for rotatably mounting the table, a plurality of
20 cutting frames in the table, a follower block for forcing a potato through the frames, arms on the block, means for swingably mounting the arms, means for oscillating the arms to swing the block into engagement with one of
25 the frames which is disposed thereunder, means for imparting intermittent rotary motion to the frame, said last mentioned means comprising a shaft having a crank arm thereon, a catch pivotally engaged with the crank
30 arm and having a catch head engageable with recesses in the bottom of the table, means for holding the catch into engagement with the table, said last mentioned means comprising a crank shaft having a spring engaged therewith to urge one end of the crank shaft in engagement with the catch to
35 hold it in engagement with the table, a stop pawl engageable with the recesses, spring means normally holding the pawl in engagement with the recesses, said pawl being in the path of movement of the catch so as to be released when the catch is in engagement with a recess and is in the
40 act of rotating the table, a connecting rod engaged with a crank on the shaft and means for engaging the crankshaft with the arms to oscillate said arms.
45

In testimony whereof I affix my signature.
50 LEWIS F. ALTFATHER.
